FIRE EXTINGUISHER

William L. Roessner, Denver, Colo., assignor to
Bertha L. MacGregor, as trustee

Application January 5, 1938, Serial No. 183,446

5 Claims. (Cl. 169—26)

This invention relates to improvements in a portable fire extinguisher wherein a plurality of frangible grenades containing fire extinguishing material is shattered by means rendered operative by heat generated by the fire to be extinguished, reference being made to my Patent No. 2,066,648, dated January 5, 1937.

In a fire extinguisher of the type indicated, it is desirable to provide a container or kit into which a plurality of frangible grenades is placed on individual supports which are each provided with heat-controlled grenade crashing means, and the container or kit being provided with porous walls through which the heat may travel, and a crimped perforated bottom wall into which the liquid flows when the grenades are shattered and which serves to retard the liquid during its outward flow from the container or kit.

It is an object of the present invention to provide a container or kit for retaining frangible grenades and which kit is constructed and arranged to permit of the circulation of heated air therein for rendering the grenade crashing means operable to shatter the grenades when subjected to the proper degree of heat.

A further object is the provision of a container or kit arranged to be supported or suspended for automatic use and provided with a bottom wall constructed to diffuse and retard the outward flow of the liquid when the grenades are crashed.

And a further object is the provision of a container or kit having individual supports for the grenades positioned in close proximity with each other and each of which supports is provided with heat-controlled grenade crashing means movable within the confines of the supports when released for operation.

Other objects and advantages will become apparent from the ensuing description and claims.

Referring to the drawing:

Figure 1 is a perspective view of the container or kit.

Figure 2 is a plan sectional view taken substantially on the line 2—2 of Figure 1.

Figure 3 is a cross-sectional view taken substantially on the line 3—3 of Figure 1.

Figure 4 is an enlarged detail perspective view of one of the grenade supporting and crashing means within the kit; and

Figure 5 is a partial detail perspective view of the bottom wall of the kit.

The container or kit is designated as 10 and is of skeleton construction comprising a back wall 11, porous end walls 12 and 13, respectively, and a porous front wall 14. A cover 15 is also provided

with porous material 16, and is hingedly attached at 17—17 to the back wall 11 and provided with a latch 18 to secure the same in closed position to the front wall 14. The bottom wall 19 of the container or kit 10 is crimped transversely of its length and the apexes 20 of these crimps are each provided with a plurality of relatively large aligned openings 21, while the valleys 22 of the crimps are provided with a plurality of relatively small openings 23.

A plurality of individual L-shaped supports 24 are arranged in close proximity with each other in the container or kit 10. These supports are secured to the back wall 11 to screws 25—25 arranged in pairs therein and the supports are provided with aligned bayonet slots 26—26 to fit over the screws 25—25 to hold the supports in position. The horizontal portion 24a of each of the supports 24 is provided with an annular opening 27 and a grenade A containing a fire extinguishing liquid is positioned in each of these openings of the supports. The supports 24 each carry a grenade crashing means designated as a whole as 28 and comprises a pair of annular members 29 and 30, respectively, arranged in superposed relation on the horizontal portion 24a of the supports and pivoted at 31 thereon. Each annular member 29 and 30 is provided with an extending portion 32 and 33, respectively, to which the free ends of a tension spring 34 are attached, and which spring serves to pivotally swing the members 29 and 30 on their pivot 31. These members 29 and 30 are retained in normal or open position with their openings 35 and 36, respectively, aligned with the opening 27 in the horizontal portion 24a of the support 24 by means of a heat responsive element 37 constructed of a fusible alloy. The grenade support 24 is also provided with a resilient U-shaped member 38 secured thereto at 39 and serves to guide the grenade and to yieldingly support the same against movement while positioned in the opening 27 of the horizontal portion 24a thereof.

In the construction of the container or kit 10, it will be noted that the skeleton frame is arranged to form legs 40 which may support the same when placed on a surface and the space between the legs 40 forms openings at the lower portion of the container or kit to permit the air to circulate under and through the bottom wall 19. A handle 41 is secured to the cover 15 and is of strap-like formation and serves to support the container or kit 10 for portable purposes, or as means for suspending the same.

In its operation, the container or kit 10, when

subjected to heat, will permit the heated air to circulate through it by means of the porous end walls 12 and 13, front wall 14 and also through the cover 15 and openings 21 and 23 of the bottom wall 19 around the grenades A. When the heat responsive elements 37 are heated to a degree to melt the same, the tension springs 34 will collapse the annular members 29 and 30 to shatter the grenades A and permit the liquid therein to flow on the bottom wall 19 which will be retarded in its passage through the openings 21 and 23 and thereby permit the liquid to partially volatilize before flowing outwardly of the kit.

15 I claim:

1. A fire extinguisher of the character described, comprising a kit having a solid back wall, porous front and end walls and a porous cover forming the top wall, a plurality of grenade supports carried on the back wall, a frangible grenade containing a fire extinguishing liquid positioned on each support, grenade crashing means carried by each support, thermoresponsive means retaining the grenade crashing means 25 releasable when subjected to a predetermined degree of heat, and a crimped bottom wall for the kit provided with small perforations in the valleys of the crimps and large openings at the apexes of said crimps.

30 2. A fire extinguisher of the character described, comprising a kit having a solid back wall, porous front and end walls and a porous cover hingedly carried on the back wall, grenade supports carried on the back wall, a frangible grenade containing a fire extinguishing liquid positioned on each support, grenade crashing means carried by each of said supports, thermoresponsive means releasably retaining the grenade crashing means releasable when subjected to 35 a predetermined degree of heat, the bottom wall of the kit being crimped and provided with small

perforations in the valleys of the crimps and large openings at the apexes of said crimps.

3. The combination of claim 2 hereof in which the grenade supports are each provided with resilient means for releasably retaining the grenades in the supports. 5

4. In a fire extinguisher of the character described, comprising a kit adapted to retain a plurality of hermetically sealed grenades containing a fire extinguishing liquid such as carbon tetrachloride or the like and arranged for manual and automatic disposal of the liquid within the grenades, the kit having a solid back wall, porous front and end walls and a porous cover forming the top wall, a plurality of grenade supports in the kit, grenade crashing means on each support including thermoresponsive means retaining the same readily releasable to crash the grenades when subjected to a predetermined degree of heat, and a crimped bottom wall 10 for the kit provided with small openings in the valleys of the crimps and large openings at the apexes of said crimps. 15

5. A fire extinguisher of the character described, comprising a kit having a solid back 25 wall, porous front and end walls and a porous cover, grenade supports carried on the back wall, a frangible grenade containing a fire extinguishing liquid positioned on each support, spring tensioned grenade crashing means carried by each 30 of said supports including thermoresponsive means for holding the grenade crashing means in tensioned position and for releasing the same when subjected to a predetermined degree of heat, and a crimped bottom wall for the kit provided with small perforations in the valleys of the crimps and large openings at the apexes 35 of said crimps for retarding and permitting the liquid to partially volatilize during its flow outwardly of the kit. 50

WILLIAM L. ROESSNER.
